US00D771707S

(12) **United States Design Patent** (10) Patent No.: **US D771,707 S**
(45) Date of Patent: **** Nov. 15, 2016**

(54) **DISPLAY SCREEN OR PORTION THEREOF
WITH ICON**

(71) Applicant: **Apple Inc.**, Cupertino, CA (US)

(72) Inventors: **Aurelio Guzmán**, San Jose, CA (US);
Jonathan P. Ive, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/540,527**

(22) Filed: **Sep. 25, 2015**

Related U.S. Application Data

(63) Continuation of application No. 29/457,330, filed on Jun. 9, 2013, now Pat. No. Des. 745,041.

(51) **LOC (10) Cl.** **14-04**

(52) **U.S. Cl.**

USPC **D14/492**

(58) **Field of Classification Search**

USPC D14/485-495

CPC G06F 3/0481; G06F 3/04817

See application file for complete search history.

(57) **CLAIM**

The ornamental design for a display screen or portion thereof with icon, as shown and described.

DESCRIPTION

The FIGURE is a front view of a display screen or portion thereof with icon showing our new design.

The broken lines in the FIGURE show a display screen or portion thereof, and form no part of the claimed design.

1 Claim, 1 Drawing Sheet
